DESIGN FOR A BRAID

Leo Beer, Kew Gardens, N. Y.

Application March 18, 1949, Serial No. 1,471

Term of patent 7 years

(Cl. D3—32)

To all whom it may concern:

Be it known that I, Leo Beer, a citizen of the United States and a resident of Kew Gardens, county of Queens, and State of New York, have invented a new, original, and ornamental Design for a Braid, of which the following is a specification, reference being had to the accompanying drawing, forming part thereof.

The figure is a plan view of a piece of braid, showing my new design.

The broken lines outline a design unit, which unit is repeated throughout the length of the braid as indicated.

In the drawing, the solid black and the shading are intended to indicate areas of contrasting color.

I claim:

The ornamental design for a braid, substantially as shown and described.

LEO BEER.
